MOTION PICTURE PROJECTOR

Mario Sassoli, Milan, Italy

Application October 2, 1937, Serial No. 166,948

5 Claims. (Cl. 88—16)

This invention relates to a small motion picture projector, particularly intended to serve as a toy for children.

One of the objects of the invention is to provide a toy cinema which is cheap, safe in operation and durable.

A further object is to provide a new apparatus involving simple motions.

Another particular object of the invention is to provide an apparatus in which a film carries out a slow and steady longitudinal motion and simultaneously a rapid intermittent transverse motion and passes through a fixed non-diaphragmed light ray.

Still another object of the invention is to provide a projector and a film on which the characters are distributed over three or more superposed rows of pictures which are projected by transverse motion of the longitudinally running film.

Still another object is to provide a projector for a perforated or non-perforated film having half the width of the usual film, this substandard film, furthermore, requiring a long time for projection and being preferably so short, say, 10 cm., that it can be mailed in an envelope without being rolled. Owing to the small consumption of material and its production from standard film, such a film is extraordinarily cheap.

By way of example, one embodiment of the invention is illustrated in the accompanying drawing, in which Figure 1 is a vertical longitudinal central section of the projector; Fig. 2, a front view of the film carrier; Fig. 3, a section on the line III—III of Fig. 1; Fig. 4, a detail view; and Fig. 5, a view on an enlarged scale of a piece of standard film subdivided into two standard films, with three rows of pictures on the lower film.

Referring to the drawing, in the casing 1 a plate 2 is inserted from below which abuts against projections 3 of the casing 1 and is detachably secured thereto by means of screws, etc. The plate 2 serves for supporting the optical equipment comprising an incandescent lamp 5 disposed in an attachment 4 of the plate and the lenses 6. Below the plate 2 a space 7 accommodates a dry battery, a transformer, etc. One pole of this source of current is directly connected by the line 8 to the socket 9 and the other pole by a conductor 10 and an outwardly extending cut-out 11 to the other contact of the lamp 5. An extension of the striplike conductor 10 shuts off the light chamber containing the lamp 5 from the space of the casing.

In the upper space of the casing 1 the mechanism for moving a film 12 is located, which is preferably inserted from below. The mechanism comprises a supporting yoke 15 which is secured to the wall of the casing by means of the flanges 13 and screws 14 and from which a guide plate 16 having a window 17 depends in vertical direction. On the plate 16 another plate 18 is vertically displaceably arranged and guided on top by a driving pin 19 and below by a screw 20 both of which members slide in corresponding longitudinal slots of the plate 16.

Between the plates 16 and 18 the film 12 moves which is guided on its upper edge by the springs 15 which are attached to the plate 18 and pass through recesses 22 thereof into the longitudinal slots 23 of the plate 16. The lower edge of the film 12 is guided by pins 24 which project from the plate 18 and engage slots in the plate 16. 25 designates an elongated clearance of the plate 16 20 located opposite a film feeding means which may consist of a wheel 26 fitted with rubber or teeth. 27 is an additional lens arranged in the casing 1 in the axis of the lenses 6 and of the window 17.

The driving pin 19 extends into a recurring 25 groove 29 arranged on the circumference of a wheel 28 and comprising three sections 29a, 29b, 29c of equal length which are superposed in staggered relation and which pass over into each other by means of the oblique connections 29d. 30 The wheel 28 is supported by a shaft 30 disposed in the yoke 15 and driven by a crank having the form of a cover 31 for the casing 1 and being provided with a handle 32.

The rotary motion of the shaft 30 is transmitted in a considerably reduced manner by means of a cord drive and an intermediate wheel to a wheel 33 which projects somewhat from the casing 1 and is connected with a portion 34a of the two-part shaft of the film feeding means 26 40 arranged in the plate 18, the two shaft portions 34a, 34b engaging each other in telescopic fashion.

The film 12 is a short strip of approximately 10 cm. length and can be mailed in an envelope of standard size without being rolled. Its width 45 is half that of standard film, and it is provided with three superposed rows of pictures 35, 36, 37 which are projected also transversely to the longitudinal direction of the film. Under the rows of pictures a broad feeding strip 38 is provided 50 which may be perforated.

The toy projector functions as follows:

After the film 12 has been pushed between the two plates 16, 18 to be caught by the feeding means 26 and after the lamp 5 has been switched 55

on the crank 31, 32 is turned, whereby the pin 19 in the groove section 29a is intermittently moved at the end of this path into the section 29b in which it remains for a period corresponding to 5 the length of the section, whereupon it passes intermittently into the section 29c to 29a, and so forth. This causes a corresponding motion of the film plate 18 which intermittently moves the film guided 10 by it transversely to the longitudinal direction thereof, so that the pictures of the three superposed rows 35, 36, 37 successively pass in front of the window 17 into the light ray and are projected on an enlarged scale by the lens 27 onto 15 a screen, not shown. During the transverse motion the film 12 is also gradually advanced due to the reduced drive of the film feeding means 26, so that the result of the combination of the longitudinal and transverse motions is a 20 zigzag-like motion of the rows of pictures 35, 36, 37 through the fixed light ray, as indicated by the arrow in Fig. 5. The wheel 33 partly projecting from the casing 1 permits adjustment of the film 12 independently of the crank drive 31, 25 32, in which case two parts slide upon one another in the cord drive.

The plate 31 can be unscrewed from the shaft 30 by being turned back. The various parts may consist of suitable material, such as wood, metal, 30 etc.

Wherever considerations of strength, etc. permit, light yet durable artificial resin masses are preferably employed. The driving and control wheel 28 may be unitary or composite construction. The cord in the reduction gear may consist of spiral wire.

I claim:

1. A motion picture projector, comprising a small casing containing a fixed optical equipment consisting of an electric lamp, a lens arrangement and current supply means, a guide plate, a film carrier plate guided on said guide plate and intermittently movable transversely into several positions, said carrier receiving and guiding a substandard film provided with at 40 least three longitudinally superposed rows of pictures, a grooved disc arranged in the casing and adapted to be driven by a hand crank and comprising sections of a groove arranged on its circumference, which correspond to the number 45 of rows of pictures and pass into one another, the position and displacement of said groove sections being arranged according to the rows of pictures, said film carrier and groove being in driving connection by means of a driving pin, a feeding means disposed on the film guide plate for continuously moving the film in longitudinal direction, said feeding means being in reducing driving connection with the drive of the grooved 50 disc, the electric lamp, a portion of the lens arrangement, and the current supply means being mounted as a unit on a mount member and the film carrier with the guide plate and the grooved disc being mounted as a unit on a second mount member, said mount members being detachably 55 connected with the casing for ready insertion into or removal therefrom.

2. A motion picture projector, comprising a small casing, a fixed optical equipment consisting of a lamp and a lens arrangement, a film carrier for receiving and guiding a film strip of substandard width provided with at least three 5 longitudinally superposed rows of pictures and means for moving the film in transverse directions relative to the fixed optical equipment to exhibit successively pictures of the superposed rows and simultaneously with such transverse 10 movement moving the film longitudinally, the lamp and a portion of the lens arrangement being mounted as a unit on a mount member and the film carrier and a portion of the operating means therefor being mounted as a unit on a 15 second mount member, said mount members being detachably connected with said casing for ready insertion into and removal therefrom.

3. A motion picture projector, comprising a small casing, a fixed optical equipment consisting of a lamp and a lens arrangement, a film carrier movably arranged relative to the optical equipment for receiving and guiding a film strip of substandard width provided with a plurality 20 of longitudinally superposed rows of pictures, 25 means for longitudinally moving the film in the carrier and means for simultaneously with and during said longitudinal movement moving the film carrier transversely to the longitudinal direction of the film successively into the positions 30 corresponding to the number of rows of pictures relative to the fixed optical equipment, the film carrier comprising pins for guiding the lower edge of the film and spring members for guiding the upper edge of the film.

4. A motion picture projector, comprising a small casing, a fixed optical equipment consisting of a lamp and a lens arrangement, a film carrier for receiving and guiding a film strip of substandard width provided with at least three 40 longitudinally superposed rows of pictures and means for moving the film in transverse directions relative to the fixed optical equipment to exhibit successively pictures of the superposed rows and simultaneously with such transverse 45 movement moving the film longitudinally, the means for moving the filaments longitudinally including a gear element projecting through the casing for ready manual engagement for adjustment of the film.

5. A motion picture projector, comprising a small casing, a fixed optical equipment consisting of a lamp and a lens arrangement, a film carrier for receiving and guiding a film strip of substandard width provided with at least three 50 longitudinally superposed rows of pictures and means for moving the film in transverse directions relative to the fixed optical equipment to exhibit successively pictures of the superposed rows and simultaneously with such transverse 55 movement moving the film longitudinally, the upper end of the casing being in the form of a rotatable disc in operative engagement with the film operating mechanism and provided with a handle for manual operation.

MARIO SASSOLI.
